FIG. 1 is a top, rear and right side perspective view of a helmet counterweight shovel head showing my new design;
 FIG. 2 is a top, rear and right side perspective view thereof;
 FIG. 3 is a bottom plan view thereof;
 FIG. 4 is a top plan view thereof;
 FIG. 5 is a left side elevation view thereof;
 FIG. 6 is a right side elevation view thereof;
 FIG. 7 is a rear elevation view thereof; and,
 FIG. 8 is a front elevation view thereof.

1 Claim, 6 Drawing Sheets**DESCRIPTION**

I claim the ornamental design for a helmet counterweight shovel head, as shown and described.
